United States Patent Office

Des. 214,511
Patented June 24, 1969

214,511

TAPE REEL OR THE LIKE

Clayton A. Laughlin, Minneapolis, Minn., assignor to Standard Oil Company, Chicago, Ill., a corporation of Indiana

Filed Dec. 11, 1967, Ser. No. 9,713

Term of patent 14 years

Int. Cl. D14—01

U.S. Cl. D26—14

Fig. 1

Fig. 2

I claim:

The ornamental design for a tape reel or the like, as shown and described.
